UNITED STATES PATENT OFFICE.

IRA EMMETT McCABE, OF LEXINGTON, NEBRASKA.

AERONAUTICS.

1,227,464.

Specification of Letters Patent.

Patented May 22, 1917.

Application filed April 11, 1913. Serial No. 760,396.

To all whom it may concern:

Be it known that I, IRA EMMETT McCABE, a citizen of the United States, residing at Lexington, in the county of Dawson and State of Nebraska, have invented new and useful Improvements in Aeronautics, of which the following is a specification.

This invention relates to improvements in aeronautics, and more particularly to a simple and efficient means for controlling the flight of an aeroplane.

It is the object of this invention to so construct an aeroplane that its lateral, horizontal and vertical movements may be completely controlled by the actuation of independently operable control planes arranged on each side of the main planes equi-distant from the vertical center thereof and ahead of the center of gravity. It is a further object of this invention to provide the main planes with a following and steadyng plane rigidly supported from the main planes which will have the required amount of lift with the minimum resistance to the turning movement of the main planes.

The advantages of this construction are obvious. In the usual type of aeroplane the ascending and descending movements are regulated by one or more horizontal planes for this purpose only usually arranged centrally of the longitudinal axis and forward of the main planes, the horizontal direction being regulated by a separately operable vertical rudder usually at the rear, and the lateral stability effected by ailerons usually arranged on each side of the main planes and connected to act in unison, thus necessitating three separate regulating means, while in the present invention all three of these results are produced by a single separately actuated control.

While the preferred form of this invention is illustrated upon the accompanying sheets of drawing, yet it is to be understood that minor detail changes may be made therein without departing from the scope thereof.

Figure 1 is a view in perspective of an aeroplane in flight, constructed in accordance with this invention, approaching at an angle.

Fig. 2 is a top plan view of Fig. 1.

Fig. 3 is an enlarged detail view in rear perspective with the upper main plane removed illustrating the connections for actuating one of the control planes.

To attain the results of this invention the control planes should be of sufficient size, arranged equidistant on each side of the vertical center of the main planes, and forward of the center of gravity of the entire machine and may be placed in any position desired so long as they satisfy these conditions, and it is also necessary that the following and steadyng plane be rigidly secured to the main plane possessing sufficient lift to fulfil its requirements and at the same time offer the minimum amount of resistance to the turning movement of the main plane in the horizontal. While a particular shape of main plane is illustrated, yet it is to be understood that this controlling mechanism can be applied to any other form of monoplane, biplane and polyplane if the control planes are placed in the relation above stated and the following and steadyng plane answers the requirements necessary to this invention.

This invention is illustrated as applied to a biplane having the greatest width in the direction of travel. As illustrated, the main supporting planes 1 and 2 are of rectilinear shape with their narrowest edges secured together and their longest edges spaced apart at the center, so that the main planes in front elevation appear to form an open ellipse. The bodies of the upper and lower main planes are of usual construction and provided with the usual covering. The curved relation of the two surfaces to each other is maintained by struts 3 between the front edges of the planes and similar struts 4 between the rear edges of the planes arranged on each side of the vertical center and a similar pair of struts 5 and 6 arranged preferably two-thirds the distance from the center to the side edges of the main planes. The necessary diagonal bracing of the wire is also provided.

The following and steadyng plane 7 comprises upper and lower rectilinear supporting surfaces similar to the main planes having their shortest edges secured together and centrally spaced apart with their longest edges arranged parallel with the longest edges of the main planes presenting an open ellipse to the direction of travel. The following and steadyng plane is rigidly secured by suitable braces 8 to the main planes in such a manner that the relation of the following and steadyng plane to the main plane is such that when the machine is

- traveling horizontally the center of gravity and the center of pressure coincide.
- The controlling or steering is produced by mounting at the forward end of each meeting edge of the main planes a control plane 9 preferably of rectangular shape with the longest edge parallel to and of equal length to the meeting edge of the main planes and preferably one-half the width.
- 5 Each control plane is preferably mounted upon a central, transverse shaft 10 mounted in bearings between the meeting edges of the main planes and extending inward to bearings upon the adjacent forward strut 5.
- 10 Adjacent to the strut 5 an angular actuating member 11 is rigidly secured to the control plane shaft. Preferably mounted on a transverse shaft 12 secured between the fore and aft set of middle cross pieces 13 of the 15 lower main plane are placed separate operating levers 14 each connected to the adjacent control plane. The lower end of each actuating member 11 is connected by a cable 15 passing through pulleys 16 on 20 the forward struts 5 and 3 on each side of the vertical center to the forward edge of the adjacent operating lever 14 with another cable 17 leading from the rear of the 25 actuating member 11 passing over a pulley 30 18 preferably arranged midway upon the after, outer strut 6 thence through a pulley 19 upon the after middle strut 4 and led to and secured behind the forward cable 15 upon the operating lever 14. By this construction and connection each control plane 35 may be turned independently about its transverse axis. Both of the cables of each set leading from the middle struts 3 and 4 to the lever 14 are preferably provided with 40 a turnbuckle 20 or other take-up means whereby the cables may be constantly kept taut and properly adjusted.
- It is preferable to construct the main plane in the form of an open ellipse, as 45 shown, which allows of triangular construction of greater strength than the separated parallel planes, and when in flight the ribbon of air passing through the curved surfaces of the open ellipse adds to the stability and substantially overcomes the tendency of the machine to side-slip. The construction of the following and steadyng plane being in the form of an open ellipse produces a sufficient lift to steady the main 50 plane and as the surfaces meet at each end will allow of a turning movement of the main plane in the horizontal with the least amount of resistance or drag. The operating levers for the control planes are prefer- 55 ably mounted to move in the direction of flight and are arranged on each side of the operator so as to be readily grasped one in each hand. As aforesaid the relation of the following and steadyng plane to the main 60 plane is such that the machine will travel 65

in the horizontal when the surfaces of the control planes are in a neutral position offering no pressure up or down. To cause the machine to ascend both levers are moved rearward which will cause the entering edge 70 of each control plane to rise so that the air will strike the under surfaces thereof moving the center of pressure ahead of the center of gravity causing the machine to ascend evenly. If it is desired to descend the levers are each moved forward which will cause the entering edge of the control planes to be depressed below the horizontal so that the air will strike the upper inclined surfaces thereof producing pressure from 75 above, moving the center of pressure behind the center of gravity and cause the machine to descend. In order to turn the machine in either direction during flight the lever on the inside of the turn is moved forward 80 which will decrease the lifting of that control plane and increase the head resistance on that side. The other control plane is brought to a neutral position or nearly so and remains stationary in that position during the turn. If a turn is desired in the 85 opposite direction the method is reversed. When the machine tips to either side from any cause during flight, it is immediately righted by raising the entering edge of the 90 control plane on the low side and lowering the entering edge of the control plane on the high side until the machine is righted and then the control planes are both brought back to the position occupied before the tipping movement occurred. 95

100 It is to be understood that an engine and one or more propellers of any desired type may be applied to this machine with the propeller either to the front or rear as desired, so long as the relations above specified are retained.

105 Since the center of gravity and the center of pressure are at the same point when the machine is in horizontal flight and as the control planes are forward the center of gravity, it is readily seen that should the engine become stalled the operator can easily volplane to the earth, because by immediately moving the operating levers forward 110 the necessary pressure upon the under surfaces of the control planes for ascending is lost and pressure from above is immediately gained, thereby tipping the machine forward. 115

120 What I claim is:

1. In an aeroplane, rigid main supporting planes joined at their outer edges to form an ellipse, a following and steadyng plane rigidly secured to the main planes, and a single control for the lateral, horizontal and vertical movements of the aeroplane comprising two separately operable coacting control planes mounted on shafts having a common axis at right angles to the direction 125

of flight, said control planes being arranged equidistant on each side of the center of the main planes and forward of the center of gravity of the aeroplane.

- 5 2. In an aeroplane, rigid main supporting planes, a following and steadyng plane comprising upper and lower plane surfaces brought together at their ends presenting an open ellipse to the direction of travel
- 10 rigidly secured to the main planes, and a single control for the lateral, horizontal and vertical movements of the aeroplane comprising two separately operable coacting control planes mounted on shafts having a common axis at right angles to the direction of flight, said control planes being arranged equidistant on each side of the center of the main planes and forward of the center of gravity of the aeroplane.
- 15 3. In an aeroplane, rigid main supporting planes, a following and steadyng plane rigidly secured thereto of such relation that in horizontal flight the centers of pressure and gravity of the aeroplane are at the same point, and a single control for the lateral, horizontal and vertical movements of the aeroplane comprising two control planes mounted on shafts having a common axis at right angles to the direction of flight ar-
- 20 ranged equidistant at each side of the center and exterior of the sides of the main planes and forward of the center of gravity of the aeroplane, said main and supporting planes comprising a plurality of members joined
- 25 to form an ellipse open to the direction of travel, and separate means for operating the control planes independently of each other to cause them to coact in controlling the movement of the aeroplane.
- 30 4. In an aeroplane, upper and lower main

plane surfaces brought together at their ends presenting an open ellipse to the direction of travel, and a following and steadyng plane of similar construction rigidly secured thereto of such relation to the main plane that in horizontal flight the centers of pressure and gravity of the aeroplane coincide, control planes arranged equidistant on each side of the center of the main planes and forward of the center of gravity, and separate means for operating each control plane independently of the other for solely controlling the lateral, horizontal and vertical movements of the aeroplane.

- 55 5. In an aeroplane, upper and lower main plane surfaces brought together at their ends presenting an open ellipse to the direction of travel and a following and steadyng plane of similar construction rigidly secured thereto of such relation that in horizontal flight the centers of pressure and gravity of the aeroplane coincide, a control plane on each side exterior of the meeting edge of the main plane centrally mounted upon a horizontal shaft passing through the forward end of each meeting edge of the main plane, a bearing for the inner end of each shaft arranged intermediate the entering edges of the main plane, an actuating member upon each shaft, an operating lever for each control plane, and a means of connection between each lever and the adjacent control plane whereby all movements of the aeroplane during flight are controlled by said levers.
